UNITED STATES PATENT OFFICE.

JOHN MICHAEL MAYER, OF KINGSTON, NEW YORK.

LAWN-SWING.

1,220,764.

Specification of Letters Patent. Patented Mar. 27, 1917.

Application filed June 9, 1916. Serial No. 102,633.

To all whom it may concern:

Be it known that I, JOHN M. MAYER, a citizen of the United States, and a resident of Kingston, in the county of Ulster and 5 State of New York, have invented a new and Improved Lawn-Swing, of which the following is a full, clear, and exact description.

Among the principal objects which the 10 present invention has in view are: to provide a structure of the character mentioned which may be closely folded; to provide a light frame; and to reduce the cost of construction of an apparatus of the character 15 mentioned.

Drawings.

Figure 1 is a side view of a swing constructed and arranged in accordance with the present invention, the same being shown 20 disposed as in service;

Fig. 2 is a side view of the same, being shown as folded and out of service;

Fig. 3 is an end view of the structure in 25 service and as seen in Fig. 1;

Fig. 4 is a detail view in perspective, showing the top of the frame and suspension bars thereof;

Fig. 5 is a detail view showing the connection between the brace bars for holding 30 in spaced relation the supporting frames of the swing structure.

Description.

As seen in the drawings, two supporting 35 frames are employed, each of the said frames having oppositely-disposed side struts 10. The struts 10 are bolted to foot bars 11 and head bars 12. The bars 12 are slightly shorter than the bars 11, thereby providing 40 a spread for the feet of the frames formed by the struts 10 and bars 11 and 12. The corners formed by the struts 10 and foot bars 11 are reinforced by braces 13.

Bolted to each of the head bars 12, are 45 strap hinges 14. Through the hinges 14 extend pivot rods 15. Bearings for the pivot rods 15 are formed in the upper extremities of the swing falls 16. Similar bearings are formed at the lower extremities of the falls 50 16, to receive the pivot bars 17.

The falls 16 are arranged in pairs, each pair supporting a swing-seat 18. Each swing-seat 18 is extended outward from each pair of falls, and is supported in part by 55 the short brackets 19 and the spreader arms

20. The outer ends of the brackets 19 are pivotally connected by pins 21, with the seat backs 22. The backs 22 are held in position by the seats 18. To this end, the backs 22 rest against the said seats, which in turn are 60 supported by cross cleats 23 extending between and rigidly connected with the brackets 19.

The struts 10 are held in spaced relation and inclined toward each other by the sills 65 24, on which the lower ends of the said struts rest, and to which they are rigidly secured by bracket arms 25. The upper ends of the struts are held in spaced relation by the pivotally united locking bars 26. The 70 bars 26 are pivotally united by a bolt 27. Each of the bars 26 is pivoted by a bolt 28 on a strut 10. The combined length of the bars 26 determines the spaced relation 75 of the upper ends of the struts 10 and frames formed in part thereby.

The bars 26 have each a hook stop 29, each stop being arranged to engage the opposite bar to hold the two bars in straight-line arrangement. The straight-line disposition of 80 the bars 26 is further maintained by the swinging links 30, which are permanently pivotally mounted on the bolts 31 in the struts 10 and are arranged for temporary engagement with the bolts 27.

The bars 26 are constructed as lightly as consistent with safety, and are reinforced by V-shaped braces 32. The braces 32 are permanently engaged by the bolts 31, and are arranged for temporary engagement by 90 means of bolts 33 and pins 34, with the bars 26 and struts 10. The V-shaped braces as shown best in Fig. 1 of the drawings, form an extended base support for the rods 26 on the struts 10.

To assist in maintaining the parallel relation of the falls 16, they are permanently connected by the cross braces 35, as best shown in Figs. 3 and 4 of the drawings.

When not in active use, the swing structure is collapsed and folded in the position substantially as shown in Fig. 2 of the drawings. In this figure, it will be seen that the struts 10 and the bracket arms 25 thereof, have been released from the sills 24, and the 100 feet or supporting ends of the said struts are drawn together. The V-shaped braces 32 and the links 30 after being released from engagement with the bars 26, permit 105 the breaking of the joint of the said bars by 110

lifting the pivotally-connected portions thereof upward. The bars 26 swinging about their pivots 27 and 28, permit the collapsing or juxtaposition of the upper ends 5 of the struts 10 or the head bars 12 thereof.

To fold the seats to correspond with the collapsed condition of the rest of the swing structure, the spreader arms 20 are broken in the center where they are pivotally connected by the bolts 36. The seats are lifted, 10 swinging on the pins 37 to the upright position shown in Fig. 2 of the drawings. This arrangement of the seats 18 permits the inward swing of the brackets 19 and the 15 seat backs 22 connected therewith, which thereafter rest against the seats 18. It will be seen that when thus arranged, the swing structure may be folded within a small compass.

20 It is equally obvious that when desired to place the swing in service relation, this is quickly and readily accomplished, it being necessary only to spread the lower extremities of the struts 10 until the bracket arms 25 25 are properly placed on the sills 24. Then by lowering the centers or the pivotal joint of the bars 26, the upper ends of the struts 10 are spread the desired distance. As the bars 26 assume the horizontal or straight-line position, the stops 29 operate to hold 30 the same until the links 30 and the braces 32 are properly adjusted and secured to the said bars 26.

When, now, the brackets 19 are opened 35 out and the spreader arms 20 are depressed to straight line, the seat backs 22 may be swung to permit the lowering of the rear of the seats 18 so that the said seats may rest upon the cleats 23. The swing structure 40 will then be found in service or active relation.

The parallel arrangement of the falls 26 and the spaced relation of the seats 18, are maintained at the lower end by the platform 45 38, the cross bars 39 whereof are pivotally

attached at one end to one of the pivot bars 17.

While the braces 26 have been herein disclosed as a single bar extending between the oppositely disposed struts, it should be understood that where desired, there may be a pair of the said braces at opposite sides of the said struts, or, in other words, two pairs of braces connecting each pair of struts. Also while the braces have been shown and 55 described as breaking the joint thereof upward, they may be arranged to break the joint downward by depressing the center of the combined braces.

It is obvious that the sills 24 may be elongated to any desired extent. When the bracket arms 25 are rigidly secured to the said sills, it will be seen that any tendency of the frame to overturn is corrected.

Claims.

1. In a swing, the combination of two supporting frames, bars connecting the frames at opposite sides, each bar being formed of two sections pivoted together and to the frames, means for locking the said bars in alinement, braces pivoted to each frame and detachably connected with the pivots of the bars, and V-shaped braces secured to the frames and detachably connected with the sections of said bars.

2. In a swing the combination of two supporting frames, bars connecting the frames at opposite sides, each bar being formed of two sections pivoted together and to the frames, a locking member mounted on the pivot of each bar and provided with a hook at each end engaging a section of the bar, braces having one end pivoted to the frames and their ends detachably engaging the pivots of said bars, and V-shaped braces secured to the frames and each detachably connected with a section of said bars.

JOHN MICHAEL MAYER.
